UNITED STATES PATENT OFFICE.

HERBERT H. WAGNER, OF ROCHESTER, NEW YORK.

PASTEBOARD BOX AND WRAPPER.

1,420,000.

Specification of Letters Patent. Patented June 20, 1922.

Application filed October 23, 1920. Serial No. 418,881.

To all whom it may concern:

Be it known that I, HERBERT H. WAGNER, a citizen of the United States, residing at Rochester, in the county of Monroe and 5 State of New York, have invented a new and useful Pasteboard Box and Wrapper, of which the following is a specification.

This invention relates to paper wrappers for pasteboard boxes of the folding type.

10 The object of the present invention is to provide an improved paper wrapper especially adapted to be united with a folding box of the type described and claimed in an application filed October 7, 1920, Serial No. 15 415,413.

More specifically put, the object of this invention is to provide a paper wrapper which will not split along the crease lines of the hinge section of said box. The provision of 20 means to prevent this splitting of the paper wrapper along the hinge lines of the box is an important feature of this case.

The process of uniting the present wrapper with the box of the application referred 25 to above is described and claimed in a Patent No. 1,363,024, dated December 21st, 1920; while the means for holding the wrapper and box during the uniting thereof is covered by Patent No. 1,363,025, dated 30 December 21, 1920.

This invention comprehends not merely the wrapper per se, but also the article of manufacture composed of the below described wrapper when combined with the 35 particular box of the application identified above.

The invention will be best understood from a consideration of the following detailed description taken in connection with 40 the accompanying drawing forming part of this specification, with the understanding, however, that the invention is not confined to any strict conformity with the showing in the drawing, but may be changed and modified so long as such changes and modifications mark no material departure from the salient features of the invention as expressed in the appended claims.

In the drawing:—

50 Fig. 1 is a perspective view looking from the back of a box covered with the paper wrapper of the present invention.

Fig. 2 is a similar view looking at the box from the opposite side.

55 Fig. 3 is a perspective view of the underneath side portions of the box after it has

been set up but before it has been folded or wrapped.

Fig. 4 is a plan view of the paper wrapper which forms the subject of the present invention, showing in dotted lines the relative position of the parts of the folding box and the wrapper before the two are united.

For a complete comprehension of the present invention, an understanding of the construction of the pasteboard box to which the wrapper is united, must be had. This box includes a main receptacle or body portion 5 and a cover portion 6, these two portions being joined together by a hinge portion 7. Crease lines 8 defining the hinge portion extend transversely of the box. These crease lines are formed by a blunt instrument, which compresses the material of the box but does not break the fibers thereof. 70 Thus, when the cover is folded over to enclose the receptacle portion, the pasteboard does not have any tendency to break along the crease lines but maintains substantially its original strength at its hinges. 80

The bottom 5 of the box has side flaps or flanges 12 and 14 and an end flap or flange 13^a. These flaps are formed by cutting or scoring the material of the box with a knife-like implement at the time the cardboard blank is formed. These lines along which the material of the box is cut are hereafter called score lines, and are to be distinguished from the crease lines wherein the box is not weakened by cutting. The cover 90 6 has side flaps or flaps 9 and 10 and an end flap 13. All these flaps are bent upwardly by a well known type of machine and their abutted edges are joined together by binding elements 11. 95

The side flaps 12 and 14 are each provided with a tab 16, which tab is made bendable inwardly by provision of a score line 16^a. Two tabs 16 form a backing for the hinge portion 7 of the box when the cover is 100 moved toward closing position, as will be understood from Fig. 2. Each score line 16^a is offset a small distance, say one sixteenth of an inch from the adjacent crease line 8; thus any tendency on the part of the tab to break along the score line 16^a will not be transmitted to the hinge line provided by the adjacent crease. The blank which forms the box is tapered slightly from one end to the other so that the cover 110 end is wider than the receptacle end. This taper is continuous and may amount, in

the box of the size indicated in the accompanying drawing, to as much as one sixteenth of an inch. Thus, when the cover is closed down over the receptacle portion it tends to remain in position due to a slight clamping action exerted by the flanges or flaps of the cover brought into frictional engagement with the corresponding portions of the receptacle.

With this understanding of the construction of the box proper, the manner in which the paper wrapper is constructed and the reasons for the features of its construction will be readily comprehended. This wrapper, as seen from Fig. 4, includes a main body part 17 having side flaps or flanges 19, 22 and end flaps or flanges 18, 18^a. The end flaps 18^a are separated from the side flaps by cuts 20, 23. The wrapper construction so far described is not believed to contain any novelty.

The flaps of each pair of adjacent flaps 19, 22 are separated by the cut-out section 25 and also by a slit 21 joined with the cut-out section, which slit has diverging branches 21^a and 21^b, whereby the three slits together form a Y. The cut-out part 25 is made at right angles to the outer longitudinal edge of each flap 19, but the cut makes an obtuse angle with the longitudinal edge of the flap 22. The cut-out portion 25, in connection with the slot 21 and one of its branches 21^a, forms a tab 26 which is adapted to be wrapped about and united to the inner face of flap 10 of the box cover. The side edges of this tab 26 extend at substantially the same angle with the end edge of said tab, this end edge being reduced in width and being provided by the slit 21. The outer edge of tab 26 extends at an obtuse angle with that edge of the flap or flap 22 provided by the cut-out portion 25. This construction, as will be seen from Fig. 2, permits the tab 26, when folded back upon flap 10, to be united directly to the box rather than to the folded end part of flap 22.

The branches 21^a 21^b of the slits 21 provide a triangular tab 24 on each side of the wrapper and adjacent the tabs 26. These triangular tabs, as seen in Fig. 2, are adapted to be folded in upon the inside face of the hinge portion 7 of the box. The branch slit 21^b, in conjunction with the slit 21, permits each flap 19 to be folded over the corresponding flanges 12 or 14 of the box, the slit 21^b extending at the same angle relative to the slit 21 that the inside edge 16^b of tab 16 makes with the bottom 5 of the box. Thus, the paper wrapper fits the tabs 16 and completely covers the same on the outside. The provision of the slots 21^a and 21^b has another purpose, namely, it allows the paper of the wrapper to stretch after the wrapper has been united

to the box and after the box cover is folded over upon the receptacle portion. It will be understood from a showing of Figs. 1 and 2 that this closing of the cover of the box after wrapping will stretch the paper over the hinge section 7. This stretching, if carried too far, will cause breaking of the paper wrapper along the crease lines 8, thus ruining the appearance of the box and making it an unsalable article. The peculiar cut of these slits, allowing the paper to stretch between the desired points, is an important feature of the present invention.

When the wrapper is united to the box, the flaps 22 will be folded about the flanges 12 and 14, and the flap 18^a will be folded about the flange 13^a. The flaps 18, 19, 22 and 18^a have a sufficiently greater width than the width of corresponding flanges of the box so that they may be pasted not only to completely cover the outside of the box, but extend down inside the box, as shown in Figs. 1 and 2. The wrapper blank is so designed, however, that no part of the paper wrapper is joined to itself, but instead, all parts are united directly to the box as a foundation. The paper wrapper may have a slight taper from end to end to allow for the corresponding taper of the box, which has been described.

What is claimed is:—

1. A wrapper for one-piece boxes of the type embodying a body portion, a cover portion and a hinge portion, the body and cover portions having side and end flanges with the cover portion foldable over the body portion, and the side flanges of the body portion each provided with an inwardly bent tab forming a backing for the hinge portion of the body, said wrapper being formed of a single sheet of paper cut to provide side flaps and end flaps to cover the body portion, cover portion, and hinge portion of the box, said sheet having its side flaps cut inwardly intermediate the ends of the box to provide tabs for the side flanges of the cover portion of the box and tabs for the hinge portion of the box, said sheet also covering the outside of said bent tabs.

2. A wrapper for pasteboard boxes of the folding one-piece type comprising a single sheet of paper, said sheet having a cut-out section intermediate its ends and extending inwardly toward the center of the sheet from two opposite sides thereof, and a slit joining each cut-out section and extending farther into the sheet, said slit having a pair of diverging branches whereby in conjunction with the adjacent cut-out section two independent tabs are formed at one side, one for the side flanges of the cover of the box and the other for the hinge portion of the box.

3. A wrapper for pasteboard boxes of the

- 1 folding type comprising a single sheet of paper, said sheet having a cut-out section intermediate its ends and extending inwardly toward the center of the sheet from two 5 opposite sides thereof, a slit joining said cut-out section and forming a continuation of one of the walls of the cut-out section and extending farther into the sheet, said slit having a pair of branches of equal length 10 whereby the slit with its two branches forms a Y so that each cut-out section in conjunction with the slits provides two independent tabs.
4. An article of manufacture comprising 15 a folding one-piece pasteboard box, and a paper wrapper for covering the exposed portions of said box; said box including a receptacle portion, a cover portion, and a hinge portion intermediate the other two portions 20 and integral therewith; said wrapper having slits therein at opposite points on its longitudinal edges, the slits each having diverging branches, the spread between said branches amounting to approximately the width of 25 the hinge portion of the box, said slits permitting stretching of the wrapper after the uniting of the same to the box and during the folding of the box.
5. An article of manufacture comprising 30 a folding one-piece pasteboard box, and a paper wrapper for covering the exposed portions of said box; said box including a receptacle portion, a cover portion, and a hinge portion intermediate the other two portions 35 and integral therewith, said hinge portion being defined by crease lines, said crease lines being parallel to each other and being formed by a blunt instrument whereby the fibers of the pasteboard are not cut; said wrapper having slits therein at opposite points on its longitudinal edges, the slits each having diverging branches, the spread between said branches amounting to approximately the width of the hinge portion of the box, said slits permitting stretching 40 of the wrapper after the uniting of the same to the box and during the folding of the box.
6. An article of manufacture comprising a folding one-piece pasteboard box, and a paper wrapper for covering the exposed portions of said box; said box including a receptacle portion, a cover portion, and a hinge portion intermediate the other two portions and joined thereto, the cover portion and 50 the receptacle portion both having integral flanges on three sides and said receptacle portion having inwardly bent tabs at the ends of the side flanges thereof, said tabs engaging the hinge portion of the box at 55 each end; said wrapper having flaps or flanges corresponding to the flanges of the box but of greater width whereby each flange of the wrapper may cover the outside wall of each corresponding flange of 60 the box as well as the said inwardly bent tabs and may also be united to the inner wall of the corresponding flange; said wrapper having a pair of tabs at opposite points, one of the tabs of each pair being united to the 65 inner wall of the hinge portion, the other tab of each pair being united to the inner wall of the side flanges of the top portion.
- In testimony, that I claim the foregoing as my own, I have hereto affixed my signature. 70
